W. P. MURPHY,
CAR ROOF.
APPLICATION FILED OCT. 26, 1918.

1,296,308.

Patented Mar. 4, 1919.

Inventor:
Walter P. Murphy
by *Paul R. Smith*,
his Atty.

UNITED STATES PATENT OFFICE.

WALTER P. MURPHY, OF NEW YORK, N. Y., ASSIGNOR TO P. H. MURPHY COMPANY, OF PARNASSUS, PENNSYLVANIA, A CORPORATION OF PENNSYLVANIA.

CAR-ROOF.

1,296,308.

Specification of Letters Patent.

Patented Mar. 4, 1919.

Application filed October 26, 1918. Serial No. 259,771.

To all whom it may concern:

Be it known that I, WALTER P. MURPHY, a citizen of the United States, and a resident of the city of New York, in the county of 5 New York and State of New York, have invented a new and useful Improvement in Car-Roofs, of which the following is a specification.

This invention relates to improvements 10 in car roofs of the type, wherein the metal roof sheets extend from eaves to eaves and are supported on a skeleton framework.

My invention relates to the means for fastening the seam covers and the means for 15 the attachment thereof to the carline.

One of the principal objects of the invention is to provide means for fastening the seam cover directly to the carline so as to move therewith. Another object is to eliminate 20 the hood casting commonly used in connection with this type of roof and thereby reduce the overall dimension of the roof. A further object is to construct a roof wherein the roof sheets are free to move 25 independently of each other and of the carlines and seam covers, within certain limits. A still further object is to prevent any water that may leak around the securing bolts from entering the car. Another object is 30 to rigidly secure the seam cover to the carline whereby the seam cover is supported at a fixed distance from the roof sheets thereby preventing the same from bearing on the roof sheet with any great force, and to 35 attain further advantages hereinafter set forth.

My invention consists in the parts and in the combinations and arrangements of parts hereinafter described and claimed.

40 In the accompanying drawings, wherein like reference numerals refer to like parts wherever they occur,

Figure 1 is a side elevation of an eaves portion of a car roof embodying my invention;

Fig. 2 is a vertical section on the line 2-2 in Fig. 1, a portion of the seam cover being broken away;

Fig. 3 is a vertical cross-section through 50 the roof in the region of the securing bolt on the line 3-3 in Fig. 2;

Fig. 4 is a vertical section taken on the line 4-4 in Fig. 1;

Fig. 5 is a perspective view of the thread- 55 ed saddle member;

Fig. 6 is a perspective view of the bolt lock;

Fig. 7 is a perspective view of the sheet metal apron;

Fig. 8 is a cross-section through the seam 60 showing the cut-away top portion of the seam; and

Fig. 9 is a cross-section through the roof similar to Fig. 3 showing a modified form of bolt lock and apron member. 65

Referring to the drawings, the invention is shown applied to a car comprising Z-bar side plates 9. Each Z-bar side plate is positioned with its web vertical and with its top flange facing in. The carline 10 extends 70 from side plate to side plate. The end portions of the carline rest on the top flanges of the side plates to which they are riveted or otherwise secured. The carline 10 is substantially T-shaped in cross-section with 75 its web portion 11 uppermost. A wooden fascia-board 12 is bolted to the vertical web of the side plate 9. The roof sheets 13 extend from eaves to eaves with their end portions resting on the top surface of the fascia 80 and have end flanges 14 turned down into a rabbet 15 in the fascia board 12. The side margins of the sheets are bent upward in an inverted U-shaped flange 16, the flanges of one sheet overlapping the flanges of the adjacent sheet, thus forming upstanding hollow seams. The overlapped flanges 16, which form the hollow seams, extend from eaves to eaves and straddle the vertical web 11 of the carline 10. A seam cover 17 of inverted 85 channel-shape in cross-section having outwardly extending base flanges 18 is arranged over the hollow seams of the roof sheets. The base flanges practically touch the body portion of the adjacent sheets, but preferably 90 mounted so as not to be clamped thereon. This seam cover straddles the roof sheet seams, its inside measurement being greater than the width of the seam so as to allow the sheets to move endwise of the car. The 95 ends of the seam cover are turned down at the eaves, the down-turned portions 19 closing the end of the seam cover and thereby preventing water from entering the car.

The top portions of the overlapped 105 flanges, which form the hollow seams, are cut away (as indicated at 20) at a suitable distance from each end of the sheets so as to permit the seam cover to be secured directly to the carline independent of the sheets. The 110

seam cover is secured to the web of the carline at each end by means of bolts 21 inserted in T-slots 21^a formed in the top edges of the web of the carline and conforming in shape and size to the shank and head of the bolt. Each one of the bolts 21 is held in position in its respective slot in the carline web by means of a channel-shaped bolt lock 22. The bolt-lock straddles the top of the carline web and is provided with a hole in its top portion so as to allow it to be slipped over the shank portion of the bolt and be seated on the top of the carline web. A sheet metal apron 23 is positioned directly over the bolt lock and is provided with a hole in its top portion so as to permit the apron to be slipped over the bolt and be seated on the top surface of the bolt lock. The apron 23 is provided along both side margins with downwardly and outwardly inclined drip flanges 24. A saddle member 25 is threaded on the bolt so as to screw down on the apron and clamp the apron and the bolt-lock securely in position on the web 25 of the carline. These saddle members act as supports for the seam covers and have their top portions shaped to fit the under side of the top portion of the seam covers. The top surface of each saddle member is provided 30 with a groove 26 extending crosswise where the bolt extends through the threaded hole in the same. The under side of the saddle member is provided with grooves 27 on each side just outside of the downwardly inclined flanges of the apron. The bolt 21 passes through an opening in the seam cover and is provided with a nut 28 on its apron and which is screwed down tightly on a washer 29 thus holding the seam cover in position. 40 Any water which may leak in around the bolt hole in the seam cover will be caught in the groove 26 in the top face of the saddle member and conducted to its side edges due to the oval shape of the top surface of the saddle washer. The water is prevented from traveling back on the under side of the saddle washer and reaching the carline web by the grooves 27 cut in the under side of the saddle casting. This arrangement causes 45 the water to fall on the inclined drip flanges 24 of the apron 23 thereby causing the water to be deflected onto the body portion of the sheets on each side of the carlines. The cutting away of the top portion of the hole 50 low seam at the eaves end of the sheets to accommodate the members for securing the end of the seam cover to the carline permits the seam cover to move with the carline without disturbing the sheets. This arrangement also permits movement of the 55 sheets crosswise or lengthwise of the car independently of the carline and seam cover.

A combined bolt lock and apron member is shown in Fig. 9 of the drawing. The bolt lock 30 shown in this figure straddles the

top of the carline web in a manner similar to the bolt lock 22. The top portion of the bolt lock 30 is provided on each side with drip flanges 31 which are curved outwardly and downwardly so as to overhang the adjacent cut-away portions of the roof sheet flanges. The drip flanges 31 of the bolt lock 30 are similar to the drip flanges 23 of the apron member 22 and cause any water falling thereon to be deflected onto the body portion of the sheets when the sheets are in an extreme position. 75

The invention is not restricted to the exact forms and arrangements shown in the drawings, nor to the particular type of car roof 80 shown and described.

What I claim is:

1. A car roof comprising spaced roof sheets movably mounted on the substructure, bolts secured to said substructure and arranged between the spaced roof sheets, seam covers straddling the spaces between the roof sheets, and saddle members for supporting said seam covers independently of the sheets, said saddle members being 90 mounted on the bolts secured to the substructure and having drainage grooves in their top and bottom surfaces. 85

2. A car roof comprising roof sheets movably mounted on the substructure and provided with flexible joints, said joints terminating short of the eaves so as to leave a space between the sheets, seam covers inclosing said joints, bolts secured to the substructure, said bolts being arranged in said 100 space and having saddle portions for supporting said seam covers, said bolts passing through the seam covers and being secured thereto, whereby the seam cover is clamped on the saddle portion of the bolt to prevent 105 the same from being clamped on the roof sheets. 95

3. In a car roof, carlines having web portions, roof sheets movably supported on each side of said web portion, bolts detachably secured to the web portion of said carline, seam covers straddling the web portion of the carline and the margins of said sheets, and saddle members sleeved on said bolts for supporting said seam covers, the top surface of said saddle members being channeled transversely at the bolts to form drains. 110

4. In a car roof, carlines having vertical web portions, roof sheets having flexible seams arranged above the web portions of said carlines, seam covers inclosing said seams, and bolts for securing said seam covers to the carlines, a portion of said seams being cut away near the eaves to accommodate said bolts, whereby the carlines 120 and seam covers are permitted to move independently of the roof sheets. 125

5. In a car roof, carlines extending from eaves to eaves, roof sheets having overlapped rebent flanges at their side margins ar 130

ranged above the carlines to form hollow seams, seam covers inclosing said seams, but spaced therefrom, bolts for securing said seam covers to the carlines, bolt locks for 5 securing the bolts to the carlines, saddle members threaded on said bolts for supporting said seam covers, said saddles being shaped to conform to the under side of the seam covers and having channels extending 10 crosswise of the saddle at the bolt, and longitudinal grooves formed in the bottom face of the saddle on each side of the bolt to prevent the backward travel of the water on the under side of the saddle.

15 6. In a car roof, carlines having a vertical web portion, roof sheets having inverted U-shaped flanges overlapping the vertical web portions of the carlines, seam covers inclosing the overlapped flanges of adjacent 20 sheets, the overlapped flanges of said sheets being cut out near their eaves ends whereby a bolt may be secured to the carlines for holding the seam covers in position.

7. In a car roof, a substructure comprising metal carlines, roof sheets having their edge portions extending from eaves to eaves and overlapped to form seams, said seams being cut away a distance from the eaves to receive a securing bolt, means for securing 25 said bolt to the carlines, a seam cover for inclosing the roof sheet seams, a support for said seam cover, said support being threaded on the securing bolt and having a channel in its top surface crosswise of the bolt hole, grooves formed in the under

30

35

side of the support, and an apron member located under said support, said apron having downwardly inclined flanges whereby the water dripping thereon is deflected into the pan of the sheet.

40 8. A car roof comprising a substructure having an upstanding bolt near the eaves, roof sheets movably mounted on said substructure on each side of the bolt, a seam cover spanning the edges of the sheets on each side of the bolt, a supporting saddle for said seam cover, said support being threaded on the bolt and having a channel in its top face extending crosswise of the bolt hole, and having grooves in its bottom 45 surface extending lengthwise on each side of the bolt and a sheet metal apron having downwardly inclined side flanges, said apron being sleeved on said bolt and clamped between the bottom face of the supporting 50 member and the car substructure.

9. In a car roof, a carline having a vertical web portion, a bolt attached to said web portion, roof sheets arranged on each side of the web portion of said carline, a seam cover 55 overlying the carline and the adjacent margins of the sheets, and a supporting saddle for said seam cover, said supporting saddle being adjustably mounted on the bolt whereby the distance between the base of the seam cover and the roof sheets may be varied.

Signed at Chicago this nineteenth day of October, 1918.
